UNITED STATES PATENT OFFICE.

ROBERT BURNS McLELLAN, OF SEATTLE, WASHINGTON.

OIL-BURNER.

1,030,419.

Specification of Letters Patent. Patented June 25, 1912.

Application filed April 3, 1911. Serial No. 618,757.

To all whom it may concern:

Be it known that I, ROBERT BURNS McLELLAN, a citizen of the United States, residing at Seattle, in the county of King 5 and State of Washington, have invented a new and useful Oil-Burner, of which the following is a specification.

My invention relates to improvements in that class of oil burners adapted to burn 10 oil as a fuel in steam-boiler furnaces, crucible furnaces, stoves, ranges, house-heating furnaces and the like.

The objects of my invention are, to provide a burner which shall be durable, simple 15 in its plan of construction, easily regulated with respect to its capability and which shall make available for useful work a larger proportion of the heat units which are inherent in the oil employed. I attain 20 these objects by a burner constructed in accordance with plans which are illustrated in the accompanying drawing in which—

Figure 1 is a view in longitudinal sectional elevation of my invention. Fig. 2 25 a longitudinal side view of same and Fig. 3 a cross-sectional view of same, looking toward the direction of the arrows from the broken line 3 shown in Fig. 1.

Similar numbers refer to similar parts 30 throughout the several views.

In oil burners of this class the highest efficiency of the fuel can be attained only when the oil employed is atomized before it reaches the point of combustion, irrespective of variations in the rate of oil consumption. Under such conditions a flame of larger volume with higher flame-temperature reaches a longer distance from the nozzle or tip of the burner. In burners 40 heretofore employed such conditions have not been readily attained. In such burners a change in the rate of flow of the oil would cause the oil to reach the point of combustion in a liquid state in the form of spray 45 or small drops which makes a smoky flame of comparatively small volume and low flame-temperature with consequent decrease in efficiency of fuel. By my invention all the oil consumed, irrespective of changes 50 in the rate of consumption, reaches the point of combustion in a finely divided state mixed with the proper proportion of oxygen for producing a flame of large volume and high flame-temperature whereby results the highest efficiency.

Referring to the drawings I will now de-

scribe the plan of construction and mode of operation of my invention.

4, illustrates the body or frame of my burner which preferably is cast in one piece 60 of metal.

5 shows a screw cap which embodies a feeding tube 6 and which is adapted to screw on to the body 4 of the burner so that the tube 6 projects into the body 4. 65

7 represents an elastic washer or gasket, of material suitable for withstanding heat, disposed between the screw-cap 5 and body 4.

8 represents a pipe-thread on the outer end of the feeding tube 6 which is adapted to connect with a pipe, not shown, leading to some source of oil supply. Such pipe should, obviously, be provided with means for regulating the rate of oil flow into the burner.

9 and 9¹ represent inlets adapted to connect with steam pipes or air-pipes, not shown, through which steam or air, or both steam and air may pass into the receiving chamber 10. From the chamber 10 through the central portion of the body lead a plurality of passages 11 formed like segments of a circle by reason of the spoke like longitudinal partitions 12. These passages 11 lead into an intermediate chamber 13 from which other passages 14 of a form similar to passages 11 lead into another chamber 15, which chamber 15 serves as an outlet chamber. The passages 11 and the passages 14 are so disposed circumferentially with respect to each other that the passages 14 are in a line with the partitions 12 as shown in Fig. 3. From the outlet chamber 15 there leads the threaded outlet 17 which is adapted to receive and connect with a pipe, not shown, suitable to serve as the tip of the burner.

The operation of my invention is as follows: Air or steam is admitted into the inlet chamber 10 through inlets 9 and 9¹ 100 by means of pipes, not shown, provided with cocks or other means for regulating the pressure or the flow of air or steam from a convenient source. Oil is then caused to flow through feeding tube 6 into the chamber 10 where the oil meets the two opposing streams of air or steam from the inlets 9 and 9¹ with the result that the oil is broken in fine spray and then forced through passages 11 into chamber 13 where it has further time to be atomized, thence the now atomized oil is forced through passages 14 110

into chamber 15 where it is joined by additional air which is forced in chamber 15 through the side passages 16. From the outlet chamber 15 the atomized oil (thoroughly mixed with air or steam in proportions regulated as desired) is forced through the threaded outlet 17 thence to the burner tip, not shown, where its combustion results in high efficiency. It will be observed that the mixed air and oil spray in its progress from chamber 10 to chamber 15 comes in contact with large areas of metal which retards or retains such portion of the oil as still is in liquid form until it becomes atomized.

Having thus described my invention, what I claim is:

In an oil burner of the class described, a feed pipe for oil, inlets adapted each for

connection with an independent source of compressed gaseous fluid, a receiving chamber, an intermediate chamber, an outlet chamber adapted to connect with a burner tip, independent side passages communicating directly between the receiving chamber and the outlet chamber, a plurality of passages extending between the receiving chamber and the intermediate chamber, in combination with a plurality of passages extending between the intermediate chamber and the outlet chamber.

In witness whereof, I have this 23rd day of March, 1911 hereunto set my hand and seal.

ROBERT BURNS MCLELLAN. [L. S.]
